LOW BED UTILITY HAND CART

Eliodoro R. Perez, 149 E. Anderson St., Stockton, Calif.

Filed Feb. 28, 1964, Ser. No. 78,819

Term of patent 7 years

(Cl. D14—3)

Fig. 1

Fig. 2

Fig. 3

Fig. 4

Fig. 5

FIG. 1 is a side elevation of the low bed utility hand cart, showing my new design.

FIG. 2 is a top plan view of such cart.

FIG. 3 is a bottom plan view of the same.

FIG. 4 is a front elevation of the cart.

FIG. 5 is a rear elevation of the same.

I claim:

The ornamental design for a low bed utility hand cart, as shown.
